A. D. GROVER

BANJO RIM

Filed Nov. 25, 1925

INVENTOR.
Albert D. Grover.
BY *John W. Munro*
ATTORNEY.

UNITED STATES PATENT OFFICE.

ALBERT D. GROVER, OF LONG ISLAND CITY, NEW YORK.

BANJO RIM.

Application filed November 25, 1925. Serial No. 71,487.

This invention relates to stringed musical instruments and has reference particularly to certain improvements in banjo construction.

- 5 The objects of my invention are: first to provide a one piece metal rim and resonator forming the body of the instrument, by the use whereof the other objects of the invention are accomplished; second, to arrange substantially all the head tightening elements inside the rim, so that there are no protruding straining hooks, nuts, etc., to mar the smooth attractive outside appearance of the rim; and, third, to afford an 10 efficient means of connecting the rim to the neck of the banjo. I accomplish these objects by means of the mechanisms illustratively exemplified in the accompanying drawings, in which:
- 15 Figure 1 is a plan view of my improved banjo showing the rim and a fragment of the arm; Figure 2 is a substantially longitudinal sectional view taken on line 2-2 of Figure 1; Figure 3 is a sectional view of the rim and neck connecting means taken on line 3-3 of Figure 2; Figure 4 is a section of the rim taken on line 4-4 of Figure 1; and Figure 5 is a similar view taken on line 5-5 of Figure 1.
- 20 Briefly stated the present invention comprises a body portion for a banjo or the like, formed of a single piece of sheet metal, and comprising a base rim, intermediate annular flange and head supporting rim section having a closed concave shaped end 25 adapted to form a resonator. The flange is provided with openings to accommodate the head tightening means and to allow egress of sound from the resonance chamber 30 between the head and resonator. A neck is connected to the base rim by fastening means, which include a metal bar embedded in the head of the neck and a screw adjustable in the bar and against the inside of the 35 base section. The usual flexible head portion is stretched over the supporting rim and held taut by means of hoops and straining screws which project through further openings in the annular flange and carry nuts adjustable 40 over the screws and against the under surface of the flange.
- 45 It has been found that an instrument of this character produces very loud, sharp tones a condition which is very desirable 50 in this class of banjo and because of the great simplicity of construction and mini-

mum number of parts involved, the completed instrument may be manufactured at a very low cost as compared with similar instruments of the usual construction. 60

Referring to the drawings, the head 10 is supported on the upper rim 11 having an annular flange 12 which projects beyond the rim 11 and is approximately parallel with the head 10. At its upper end the rim 11 is spun to form a curved edge 13 which is integral with a concave-shaped bowl or resonator 14 closing the upper face of the rim, as clearly illustrated in Figure 2. A base rim 15 is spun from the outer periphery of flange 12 and comprises an annular portion approximately concentric with and parallel to the upper rim 11. The free or lower end of the base rim 15 is turned inwardly to form a bead or flange 16, thereby increasing the strength of the rim and also presenting a neat appearance. It is to be noted especially in connection with the rim and resonator just described that the entire unit is spun or stamped from a single blank of sheet metal. 75

A neck 17 of any suitable design is attached to the rim by one or more screw connections 18, each of which projects through an opening 19 in the wall of the base section 15 and into the heel of the neck 17, and which is adjustable in the threaded opening 20 of a bar 21 disposed in the heel of the neck, as illustrated clearly in Figures 2 and 3. The head of the screw 18 is seated against a washer 22 on the inside surface of the base rim section 15. Adjustment of the screw 18 to tighten the connection will result in the rim and neck being brought 95 tightly together.

The usual head 10 of parchment or calfskin is stretched over the turned edge 13 of the upper rim portion 11 and the marginal periphery of the head is arranged about a flesh hoop 23, which is held under tension by means of a hoop 24 and straining hooks 25. The lower ends of the latter hooks 25 project through openings 26 in the flange 12 and carry nuts 27 adjustable against the under surface of the flange to stretch the head 10 and keep it taut. 100

The bar 21 arranged in the neck comprises a rectangularly shaped piece which is driven into a hole 27 drilled in the heel of the neck 17, and as a consequence, the corners of the bar being of sufficient dimensions, cut into 105

- 65

the wall of the opening 27, and the bar is thus firmly locked or wedged in position so as to provide a permanent anchor for the screw connection 18.

Sound is emitted from the resonance chamber between the head 10 and resonator 14, through an opening 28 in the center of the resonator itself and through a series of openings 29 in the flange 12, the latter openings being arranged in the spaces between the straining hook openings 19.

A suitable tail piece 30 is carried by the flange 12 and provided with a plurality of projecting string fingers 31 in which the strings 32 are anchored at one end, the bodies of the strings being alined over a bridge piece 33 resting on the head 10 in the usual manner.

The construction herein described is admirably adapted for what is known as a banjo-uke which must of necessity be simple mechanically and capable of production at a moderately low price.

What I claim is:

1. In a banjo, a rim and resonator formed from a single blank and comprising an integral base rim, intermediate annular flange,

and head supporting rim having a concave back portion forming a resonator, a neck for said base rim, and connecting means for the rim and neck comprising a bar wedged in an opening in said neck and having a threaded bore disposed parallel with the longitudinal axis of the banjo, and a screw adjustable in said bore and against the inner face of the base rim.

2. In a banjo, an integral rim and resonator formed from a single blank and comprising upper and lower rim sections of different diameters and a concave resonator portion depending inwardly from the smaller upper rim section.

3. In a banjo, an integral rim and resonator formed from a single blank and comprising upper and lower rim sections of different diameters, an annular perforated portion between the two rims and disposed at right angles to the rims, and a concave resonator portion having a small center opening and depending inwardly from the smaller upper rim section.

In testimony whereof I affix my signature.

ALBERT D. GROVER.
